TIMING DEVICE

Marcus H. Rhodes, Hartford, Conn., assignor to
 M. H. Rhodes, Inc., Hartford, Conn., a corporation of Delaware

Original application October 25, 1943, Serial No. 507,640, which is a division of application Serial No. 349,119, August 1, 1940. Divided and this application October 1, 1945, Serial No. 619,681

2 Claims. (Cl. 194—72)

1

This invention relates to timing devices, and with regard to certain more specific features, to coin-controlled timing devices for indicating the passage of a purchased length of time, as for parking automobiles or the like.

This application is a division of my copending application Serial 507,640, filed October 25, 1943, now abandoned, which in turn is a division of and was copending with my application Serial No. 349,119, filed August 1, 1940, now Patent 2,369,688.

Among the several objects of the invention may be noted the provision of a coin-controlled timing device of the class described which is adapted to indicate at all times what portion of a purchased length of time has passed; the provision of a device of the class described which during the period of time which has been purchased, displays the coin employed in setting, but does not so display it during the time consumed over and above the purchased time; and the provision of a device of the class described which is substantially fool-proof in operation, simple in construction, and which may be economically made. Other objects will be in part apparent and in part pointed out hereinafter.

The invention accordingly comprises the elements and combinations of elements, features of construction, and arrangements of parts which will be exemplified in the structures hereinafter described, and the scope of the application of which will be indicated in the following claims.

In the accompanying drawings, in which is illustrated one of various possible embodiments of the invention:

Fig. 1 is a front elevation of a device embodying the present invention;

Fig. 2 is a section taken along the line 2—2 in Fig. 1, but on an enlarged scale;

Fig. 3 is a section taken along the line 3—3 in Fig. 2;

Fig. 4 is a section similar to Fig. 3, but showing a different position of the mechanism; and

Fig. 5 is a section taken along the line 5—5 in Fig. 2.

Similar reference characters indicate corresponding parts throughout the several views of the drawings.

The device of the present invention is particularly adapted for use as a so-called "parking meter" which is usually installed in connection with designated parking spaces for automobiles along the curbs of city streets. The timing device itself is usually mounted on a post on the

2

curb in proximity to the designated parking space. The device is adapted to receive a coin from a person parking his automobile in the designated space, and has means thereon for indicating a duration or period of time corresponding to the length of time a person is entitled to park in the designated space in return for the value of a coin presented.

One of the principal features of the present invention is that it indicates progressively the gradual expiration of the purchased time interval, as determined by the value of a coin initially deposited in the device.

The present invention likewise employs the coin used in initiating operation of the device as an additional signal to patrolling officers and to the public, that the space is being occupied either legally or illegally. Neither is it possible for collectors or mechanics to cheat the municipality by removing from the device the coin which is employed as a signal, as above referred to. Likewise the device of the present invention prevents removal of a coin once it has been inserted in the coin chute.

Referring now to the drawings, Fig. 1 shows a device in which numeral 1 indicates a rectangular casing which has a semi-circular top portion. The top part of the front of the casing 1 has a semi-circular opening 2 preferably holding a glass.

Back of this is a scale 3 upon which are figures to indicate the amount of legal parking time remaining. In front of this scale and movable thereover by the clockwork mechanism is a semi-circular shield 4 which, upon initiating operation of the device, is rotated until it is substantially invisible. In initiation of the operating of the device is carried out by means of a handle 5 (see Fig. 2) which operates the setting mechanism upon the insertion of a coin into the coin slot 6. Shield 4 is attached to a shaft 7 which is rotated by the clockwise mechanism.

The back of the device is provided with a viewing disc 10, arranged opposite the place where the coin is held during legal operation of the device, and also with an appropriate lock such as a screw lock 11.

Referring now to Fig. 2, the device has an appropriate coin receptacle 12 for permanent retention of coins. The receptacle 12 is preferably removable from the device so the collector can merely replace it with an empty box and take the coin containing receptacle to a central collecting point. If the receptacle 12 is of the type which automatically locks upon removal from the device, accurate records of receipts from a

3

specific device may be kept, and fraudulent returns by the collector are made difficult. A temporary coin receiver 13 is connected to receptacle 12 and opposite receiver 13 is located a viewing glass 10 which may preferably be constructed of magnifying glass.

Fig. 3 shows the device ready for the reception of a coin. Numeral 14 indicates a circular wall or cylinder which is preferably formed integrally with a plate 15, as by die casting, and acts 10 integrally with a plate 15, as by die casting, and acts to prevent insertion of a coin except at the intended place. The cylinder 14 is not a complete cylinder, it being provided with a relatively wide opening 16 adjacent the arm 21 which will be described in more detail hereinafter. The plate 15 is rotatably mounted upon a shaft 17, upon 15 which is also mounted the handle 5. The opposite end of shaft 17 carries cam 18 which cooperates with member 19, mounted on plate 15 and by pin 60, to cause rotation of the plate 15 and cylinder 14 in one direction, but not in the other. Spring 20 mounted on plate 15 retains member 19 in position for cooperation with cam 18.

On plate 15 are arms 21 and 22 movably mounted by means of rivet 23. Spring 24, attached to plate 15 by means of rivet 25 and to arm 21 at opening 26, positions arm 21 in the proper relationship to the remainder of the device. Similarly, arm 22 is positioned by spring 27 attached to plate 15 by rivet 28 and to arm 22 by opening 29. Spring 24 is stronger than spring 27 and they are adjusted so that in the Fig. 3 position spring 27 is elongated. Projection 30 on arm 21 which projects through opening 31 in plate 15, controls and limits the movement of arm 21 in cooperation with wedge 32 located between plate 15 and the back of the device.

Located below plate 15 is coin holder 33 adapted to temporarily suspend the coin opposite viewing window 10 prior to deposit thereof in coin box 12. The coin is held by bar 34 which projects thereunder. Projecting portion 35 of holder 33 cooperates with hook 36 on arm 22 to drop the coin when the device is operated to reset it. Arm 22 is curved outwardly as shown in the drawing so that the hook 36 is in the same plane as projecting portion 35 and will not engage the circular wall 14. Positioned adjacent the member 33 is V-shaped element 37, mounted on pin 38. Element 37 cooperates with cams 39, located on the screw lock 11, to drop the coin from holder 33 into coin box 12 as lock 11 is opened.

In front of the setting mechanism is located a triangular shaped dog 40. It is mounted on the shaft 7 which carries the clockwork mechanism indicated generally at 41. The dog 40 winds the clockwork mechanism upon initiation of operation of the device by the plate 15 and members assembled therewith. Lug 42 (see Fig. 2) on arm 21 is positioned to contact dog 40 under certain conditions of operation, and carry out the winding operation.

The operation of the device is as follows:

When the plate 15 assembly is in the position shown in Fig. 3 with the opening 16 opposite the coin chute 6, it is ready to receive a coin 43 which is inserted through the coin slot 6 and drops into the semi-circular segment 49 of arm 21, as indicated. A movable coin-retaining member 61 prevents removal of the coin after insertion. If the handle 5 is now rotated, carrying with it plate 15 and assembly, projecting

portion 30 attached to arm 21 contacts wedge 32 tensioning spring 24 and moving arm 21 toward the center of the assembly. This permits the coin 43 to assume by gravity the position shown in Fig. 4, where it is held between the minor semi-circular segment 44 of arm 21, and the interior wall 45 of the case 1. This retains the tension in spring 24, while at the same time the tension in spring 27 has been released because the pin 46, attached to arm 21, which imposed the tension upon spring 27 through arm 22 as shown in Fig. 3, by the movement of arm 21, has been moved away from the projecting portion 47 of arm 22. With the coin in position as shown in Fig. 4, lug 42 on arm 21 is brought into position to contact dog 40, as shown in Fig. 4.

Releasing the tension in spring 27 has dropped arm 22 to the position likewise shown in Fig. 20 4, where it contacts projecting portion 35 of holder 33 by means of hook 36. Further rotation of the handle 5 and the plate 15 assembly trips the coin holder 33 to drop the coin held temporarily before window 10 into the coin box 13, and likewise begins winding the timing mechanism.

Continuing rotation of the handle 5 until the arm 22 has passed holder 33, allows holder 33 to fall back into position by gravity, but continues winding the clockwork mechanism. This winding continues until the opening 16 is brought 30 opposite the coin slot 48, which connects with the temporary coin receiver 13. When the coin 43 reaches this position, it is discharged into the temporary coin holder, releasing the tension on spring 24, so that the device is again in the condition shown in Fig. 3.

As soon as the winding of the clockwork mechanism, by means of dog 40, ceases, as by the 40 operator releasing handle 5 or by the dropping of coin 43 into the temporary coin receiver 13, the clockwork begins to drive the shield 4 over scale 3. The winding mechanism and the clockwork are adjusted so that sufficient winding is given by the rotation of dog 40, as described above, to operate the shield 4 over the scale 3. 45 for the full time or any portion of time purchased.

Referring now to Fig. 5, a member 50 is mounted on shaft 7 to be rotary with the clockwork mechanism. This member has a projecting portion 51 which cooperates with a V-shaped member 52 rotatably mounted on a pin 53 to operate coin holder 33 through projection 35. The projection 51 is positioned so that upon expiration of the purchased parking time, this projection contacts V-shaped member 52, and moves the temporary coin holder 33 to drop the coin into the coin box 12. The coin therefore drops into temporary coin receiver 13 upon initiation of 55 operation of the device, and is dropped therefrom into coin box 12 as soon as the purchased time has been exhausted. The presence of the coin, therefore, which is visible through window 10, 60 acts as a signal to the patrolling officer and to the public that the device is measuring purchased time, rather than overtime.

Practically as soon as the parker commences to turn the crank and before lug 42 contacts dog 70 40 to set any time, the previous parker's coin is automatically dropped into the coin box if it has not already dropped upon occurrence of one of the events previously described. This dropping of the previous coin sets up an indication to the 75 patrolling officer, to the parker, and to the public.

One coin does not contact another in the winding mechanism, so that there is no possibility of two coins telescoping. The presence of the window 10 on the back of the device operates as a signal to the patrolling officer through the presence or absence of a coin showing there-through.

If preferred, the alternative form of the invention shown in Figs. 11, 12, 13, and 14 of my above-mentioned copending application Serial No. 507,640 may be employed. This embodiment is particularly useful where the meter is to operate with coins of different values to provide a corresponding purchased time interval. In this instance, however, the coin receiving member 21 shown herein would be employed in lieu of the coin receiver 62 shown in said Figs. 11-14.

In view of the above, it will be seen that the several objects of the invention are achieved and other advantageous results attained.

As many changes could be made in the above constructions without departing from the scope of the invention, it is intended that all matter contained in the above description or shown in the accompanying drawings shall be interpreted as illustrative and not in a limiting sense.

I claim:

1. A coin-controlled timing device comprising a clockworks mechanism, a manually rotatable coin carrier, a coin receiver having a coin receiving space mounted on said carrier, means for permitting the insertion of a coin into said space at one rotated position of the carrier, means for releasing the coin from said space at a second rotated position of the carrier, means forming a driving connection for winding and setting said clockworks when the carrier is rotated between said rotated positions of the carrier with a coin positioned in said space, a temporary coin holder comprising a passageway for receiving a coin released from said space at the second rotated position of the carrier and a pivoted stop member normally blocking the passage of a coin through said passageway and adapted to be pivoted to a coin releasing position, a permanent

5 coin holder for receiving coins released from the temporary coin holder, means for temporarily pivoting said stop member to coin releasing position upon the initiation of a winding operation, and means for pivoting said stop member to coin releasing position upon completion of unwinding of the clockworks mechanism.

2. A coin-controlled timing device comprising a clockworks mechanism having a rotatable shaft 10 by means of which the clockworks may be wound and set and which is returned to an original position upon unwinding of the clockworks, a manually rotatable coin carrier, a coin receiver having a coin receiving space mounted on said carrier, means for permitting the insertion of a coin into said space at one rotated position of the carrier, means for releasing the coin from said space at a second rotated position of the carrier, a temporary coin holder comprising a 15 passageway for receiving a coin released from said space at the second rotated position of the carrier and a pivoted stop member normally retaining the coin in said passageway and adapted to be pivoted to a coin releasing position, a permanent coin holder for receiving coins released 20 from the temporary coin holder, engaging means operable when a coin is in said space of the coin receiver and the coin carrier is rotated between said rotated positions for engaging the shaft of said clockworks to wind and set the clockworks and for pivoting the stop member to release any coin in the temporary coin holder at the initiation of the winding operation, and means on said shaft for again pivoting the stop member to coin 25 releasing position when the shaft is returned to said original position by the clockworks.
